UNITED STATES PATENT OFFICE.

CHARLES C. MOORE, OF NEW YORK, N. Y.

IMPROVEMENT IN APPLICATION OF WIND-POWER TO PRODUCE A RECIPROCATING MOVEMENT.

Specification forming part of Letters Patent No. 36,101, dated August 5, 1862.

To all whom it may concern:

Be it known that I, CHARLES C. MOORE, of the city, county, and State of New York, have invented a new and useful Improvement in Applying the Power of Wind-Wheels to the Driving of Machinery having a Reciprocating Movement; and I do hereby declare that the following is a full, clear, and exact description of the same, reference being had to the accompanying drawings, making a part of this specification, in which—

Figure 1 is a vertical central section of my invention, taken in the line $\alpha\alpha$, Fig. 3; Fig. 2, a horizontal section of the same, taken in the line $\gamma\gamma$, Fig. 1; Fig. 3, a plan or top view of the same.

Similar letters of reference indicate corresponding parts in the several figures.

The object of this invention is to transmit in the simplest possible manner the power from a wind-wheel shaft to the machinery to be driven, and by such a means which will not in the least degree interfere with the proper traversing of the cap in which the bearings of the wheel-shaft are placed, and will at the same time admit of the journals of the wheel-shaft having an equal pressure on each of its bearings, so as to insure an easy working of the moving parts attended with a comparatively small degree of friction.

To enable those skilled in the art to fully understand and construct my invention, I will proceed to describe it.

A represents a vertical shaft, the lower end of which is permanently secured in a proposed base, B, and C is a cap, into which the upper end of the shaft A is fitted loosely, so that the cap C may turn freely upon it, the upper end of the shaft being cylindrical to admit of that result. The cap is secured on the shaft A by means of pins a , which pass horizontally into the cap and have their inner ends fitted in a groove or recess, b , made circumferentially in it, as shown clearly in Fig. 1. The lower end of the cap C may rest on the upper end of a collar, D, which is secured permanently on the shaft A.

E is a vane which is provided with two pendants, $c c$, in which are the bearings of a shaft, G. These pendants are at opposite sides of the cap C and at equal distances from it. The shaft G passes through the cap C, which also serves as a bearing for it.

F is a wind-wheel, which may be constructed in any suitable manner, and is secured to one end of the shaft G. The vane E is in line with the shaft G and projects back a suitable distance from the cap C, to cause the wind-wheel to face the wind at all times. (See Figs. 1 and 2.)

The wind-wheel shaft G is provided with two cranks, $d d$, which are in the same plane and have each a pitman, e, attached, the lower ends of which are connected by bolts f to a slide, H, on the upright shaft A. This slide H has a groove, g, made circumferentially in it to receive a band, I, in which the slide H is allowed to turn freely, the latter having two movements—to wit, an up-and-down movement on shaft A and also a rotary one.

The band I may be formed of two equal parts connected at journals $h h$, on which the piston-rods $i i$ of two pumps are hung, the journals being at opposite points on the band, as shown clearly in Fig. 3.

From this description it will be seen that when the wheel F rotates the cranks $d d$ and pitmen $e e$ will give a rising-and-falling movement to the slide H, and the latter will of course communicate the same movement to the piston-rods $i i$; and it will also be seen that the wind-wheel E will be allowed to turn so as to face the wind in consequence of the slide H being allowed to turn within the band I. By having a pitman e at each side of the cap C, as shown, an equal pressure is obtained on each bearing of the shaft G, and all the working parts are made to operate with but little friction.

The working parts may be covered by a case, J, fitted on the base B, and the case covered by a hood, K.

Having thus described my invention, what I claim as new, and desire to secure by Letters Patent, is—

The combination and arrangement, with a wind-wheel, F, of the double-crank shaft G, cap C, shaft A, pitmen $e e$, slide H, and band I, with rods $i i$ attached, as and for the purpose herein set forth.

CHARLES C. MOORE.
